(57) **CLAIM**

The ornamental design for a body spray, as shown and described.

DESCRIPTION

FIG. 1 is a front perspective view of the body spray showing my new design;

FIG. 2 is a rear elevational view thereof;

FIG. 3 is a front elevational view thereof;

FIG. 4 is a bottom plan view thereof;

FIG. 5 is a top plan view thereof;

FIG. 6 is a left side elevational view thereof; and,

FIG. 7 is a right side elevational view thereof.

The broken line showing of the threaded connector in FIG. 1 is for purposes of illustration only and forms no part of the claimed design.
